UNITED STATES PATENT OFFICE.

AUGUST S. HELD, OF FREEPORT, ILLINOIS.

COMBINED MOP AND SCRUB-BRUSH.

SPECIFICATION forming part of Letters Patent No. 729,581, dated June 2, 1903.

Application filed October 10, 1902. Serial No. 126,685. (No model.)

To all whom it may concern:

Be it known that I, AUGUST S. HELD, a citizen of the United States of America, residing at Freeport, in the county of Stephenson and State of Illinois, have invented certain new and useful Improvements in a Combined Mop and Scrub-Brush, of which the following is a specification.

This invention has for its object the production of combined mops and scrub-brushes so contrived and arranged that they may be used both in such combination and separately; and it consists of certain new and useful features of construction and combinations of parts especially devised to those ends, all as hereinafter fully described, and specifically pointed out in the claim.

Referring to the accompanying drawings, which form a part of this application, Figure 1 is a top plan view of a combined mop and scrub-brush embodying my invention and adapted to be used for both mopping and scrubbing. Fig. 2 is a section at the dotted line 2 3 in Fig. 1 of parts there shown. Fig. 3 is a like section, also at such dotted line 2 3 in Fig. 1, showing the movable jaw of the mop-head pushed away from its fixed jaw by means of its controlling bushing or nut in order that the brush-attaching plate thereof 30 with its brush may be detached therefrom. Fig. 4 is an isometrical detail of the brush-attaching plate.

A is a fixed clamping-jaw provided with a handle-socket A' and having a channel A² extending along lengthwise of the lower and straight edge thereof.

B is a movable clamping-jaw parallel with the fixed jaw A, having its ends B' extending and converging rearwardly and united by 40 means of the interiorly-threaded nut B², through which such ends B' are inserted.

C is an exteriorly-threaded bushing turned into and operating the interiorly-threaded nut B² and the movable jaw B connected therewith.

D is a handle inserted through the bushing C and nut B² into the socket A' in the fixed jaw A, whereto it is secured.

E is a brush-attaching plate having a flute E' formed therein lengthwise thereof and 50 adapted to fit into the channel A² in the fixed jaw A and to admit the movable jaw C.

F is a furicated spring fast to the brush-attaching plate E and adapted to bestride and clasp the handle D or socket A' of the fixed 55 jaw A.

G is a scrub-brush secured to the brush-attaching plate by means of screws G'.

H is a mop inserted between the jaws A and B.

The movable jaw B is clamped against the plate E and mop H by rotating the bushing C by means of the ears C' thereon.

By loosening the jaw B and pressing downward upon the plate E the brush G may be 65 disengaged from the mop-head, thus leaving the mop and brush to be used separately, if desired.

What I claim as new, and desire to secure by Letters Patent, is—

In a utensil of the class described, in combination, a fixed clamping-jaw, having a channel extending along lengthwise of the lower and straight edge thereof and provided with a handle-socket, a movable clamping-jaw parallel with the fixed jaw, releasable means for clamping the movable jaw against the fixed jaw, a handle inserted into the socket in the fixed jaw, a brush-attaching plate having a flute formed therein lengthwise thereof and 70 adapted to fit into the channel in the fixed jaw and to admit the movable jaw, a furicated spring fast to the brush-attaching plate and adapted to bestride and clasp the handle, and a scrub-brush secured to the brush-attaching plate, substantially as and for the purpose specified.

In testimony whereof I have signed my name to this specification in the presence of two subscribing witnesses.

AUGUST S. HELD.
